UNITED STATES PATENT OFFICE.

HUGH WALLACE AITKEN, OF GLASGOW, SCOTLAND.

CRUSHING OF SUGAR CANE.

Application filed October 23, 1926, Serial No. 143,744, and in Great Britain April 27, 1926.

This invention relates to the crushing of sugar cane and particularly to the rollers employed in sugar cane mills or crushers.

In the preliminary or first crushing of sugar cane it is desirable:—

(1) To thoroughly break the cane e. g. by sharp ridges on the surfaces of the rollers.

(2) To thoroughly squeeze the cane between the surfaces of the rollers so as to press out as much as possible of the juice.

In this connection it is of course an objection if the configuration of the surfaces of the rollers allows a certain amount of the cane to pass through unsqueezed or insufficiently

squeezed: to prevent this it is necessary that the distance between the pressing surfaces of the co-acting rollers should be constant or uniform.

(3) To provide channels or the like for the escape of the expressed juice on the feed side of the co-acting rollers. In the absence of such provision the expressed juice is liable to be, and is in fact, re-absorbed by the bagasse, so that the work of expression is to a large extent lost.

Each of the three desiderata above mentioned has been provided in sugar cane mills and crushers; but, as far as I am aware, all three have not been provided in the one pair of co-acting rollers. It is the object of the present invention to provide all three desiderata in the one pair of co-acting rollers so that with this single pair of rollers a very efficient action on the cane is obtained and a very effective discharge of juice.

To make clear what has already been tried or proposed, and the improvement effected by the present invention, it may be mentioned that co-acting rollers have been employed with intermeshing ridges, the ridges being arranged at an angle of 20 to 45 degrees to the axis of the roller and placed zig-zag, that is in sections, successive sections being inclined in opposite directions. (When

in this specification it is stated that a line on the surface of the roller is at a certain angle to the axis of the roller what is meant is that the said line is at the said angle to an imaginary intersecting line on the surface of the roller parallel to the axis.) The ridges on the one roller do not, however, as a rule fill the furrows or hollows on the other so that, although the cane is broken, it is insufficiently squeezed. It has also been proposed to form or provide channels or gutters in the surfaces of the rollers, or channels or

gaps in the ridges on the same, to allow of the escape of the juice in a circumferential direction. These gaps and channels provide an opportunity for cane to pass through between the rollers unsqueezed—a serious objection.

According to the present invention the three desiderata hereinbefore mentioned are obtained in the one pair of co-acting rollers—these rollers having inter-meshing ridges backwardly inclined at a suitable angle (as will be hereinafter explained) to the axes of the rollers, the said ridges providing between them furrows for the escape of the expressed juice—by the provision of channels on the surface of one roller, these channels being at right angles to the axes of the rollers, the other roller being furnished with projecting bands which enter and roll within the said channels, filling or almost filling the same, these channels communicating with the rear ends—considered as regards the direction of motion of the surface of the roller—of the said furrows and serving to carry away the expressed juice.

The carrying of the invention into effect in one convenient manner will now be described, reference being had to the accompanying drawings.

It is usual for two co-acting rollers to be arranged one above the other—and such an arrangement will be assumed in describing the application of the present invention—but the axes of the rollers are not necessarily—and usually not in practice—in the same vertical plane.

Figure 1 is a plan of a portion of the surface of the lower roller.

Figure 2 is a section on the line A, B of Figure 1.

Figure 3 is a section on the line C, D of Figure 1.

Figure 4 is a plan of a portion of the surface of the upper roller.

Figure 5 is a section on the line E, F of Figure 4.

Figure 6 is a section on the line G, H of Figure 4.

Figure 7 is a front elevation of a pair of rollers, in which however only a part of the formed surface of the rollers is shown.

Referring to the drawings, the lower roller is provided with ridges *a* of rounded or arched section. These ridges are inclined at an angle of 45 degrees to the axis of the roller. They are arranged zig-zag, that is

successive ridges are inclined in opposite directions. The arrangement of the ridges provides hollows or furrows *b*, as shown, between the ridges.

5 At every alternate plane of division between the sections of ridges, channels *c* are formed. These are of section shown in Figure 2. They are at right angles to the axis of the roller. The furrows *b* of each section 10 communicate at their rear ends (considered as regards the direction of motion of the surface of the roller) with one of these channels.

15 The arrow *p* indicates the direction of movement of the portion of the surface of the lower roller shown.

The upper roller is provided with ridges *f* which separate rounded hollows or furrows *g*. The upper roller is also provided 20 with projecting bands *h* arranged at right angles to the axis of the roller and so placed as to enter the channels *c* on the lower roller.

25 The ridges *f* are made to conform in section with that of the furrows *b*, and the furrows *g* are made to conform with the section of the ridges *a*; and the construction and arrangement is such that in the co-action of the two rollers the ridges on the one enter, and fill or almost fill, the hollows on the other. 30 Moreover, the bands *h* are made to conform in section to the channels *c*, the construction and arrangement being such that the bands fill or almost fill the channels. There is consequently no opportunity afforded for cane 35 to pass through between the two rollers unsqueezed or insufficiently squeezed. This is a matter which it is of importance to note; it is of very great moment.

40 The ridges *f* are of a form very suitable for breaking the cane.

45 It is not necessary that the angle of the ridges to the axis of the roller should be 45 degrees. It is however necessary—as will be obvious from what has heretofore been said—that the ridges must be backwardly inclined and that the rear ends of the furrows *g* must communicate with the channels *c*. This I consider is a generally desirable angle, but it may be varied between 20 degrees and 50 70 degrees.

If desired, the channels may be cut in the roller at every, instead of every alternate, plane of division between the sections of ridges.

55 It is usual (as before mentioned) for the one roller to be above the other, but such an arrangement is not necessary for the application of the present invention.

Having thus described my invention, what 60 I claim as new and desire to secure by Letters Patent is:—

1. A pair of coacting rollers having substantially V-shaped cameo and intaglio portions upon their respective peripheral surfaces, one of said rollers having a plurality

of equi-spaced peripherally disposed channels formed therein throughout its length and a plurality of substantially V-shaped peripheral channels formed therein arranged between said equi-spaced channels and having their opposite ends communicating therewith, ridges formed upon the peripheral surface of the other of said rollers and adapted to intermesh with said channels of the first mentioned roller and said intermeshing ridges and channels disposed upon the peripheral surfaces of said rollers extending completely around each V-shaped cameo and intaglio portion thereof.

2. A sugar mill comprising a lower roller having a series of equi-spaced circumferentially disposed channels formed in the peripheral surface thereof, a plurality of coincidentally disposed V-shaped ridges on the peripheral surface of said lower roller and arranged in nested positions, the opposite ends of said ridges terminating with said channels, an upper roller having projections arranged to enter said channels and said upper roller having furrows formed in its surface for receiving said ridges of the lower roller.

3. A pair of coacting upper and lower rollers for the crushing of sugar cane and for the expression of juice therefrom, said lower roller having a series of equi-spaced peripheral channels formed therein throughout its length, a plurality of relatively wide and coincidentally disposed V-shaped ridges on the peripheral surface of said lower roller and arranged in nested positions between said channels, said ridges each being of an arched formation in cross section, the peripheral surface of said lower roller having furrows formed therein, one of which being positioned between each ridge thereon and the opposite ends of said furrows communicating with said channels, projecting bands formed on the peripheral surface of said upper roller and adapted to enter the channels of said lower roller, ridges formed on the peripheral surface of said upper roller and having rounded furrows formed within said upper roller between said ridges and said ridges and furrows of the rollers having intermeshing engagement.

4. A pair of coacting rollers for the crushing of sugar cane and the expression of juice therefrom, one of said rollers having a series of equi-spaced peripheral channels formed throughout the length thereof, a plurality of coincidentally disposed V-shaped ridges on the periphery of said rollers between the channels thereof and arranged in relative nested positions, the other of said rollers having furrows therein for the reception of said ridges and projecting bands adapted to be received in the channels of the first mentioned roller.

5. A pair of coacting rollers for the crush-

ing of sugar cane and the expression of juice therefrom, one of said rollers having a pair of circumferentially disposed channels formed in the periphery thereof, a series of relatively wide V-shaped ridges arranged in nested positions between said channels the other of said rollers having V-shaped furrows formed in the periphery thereof for the

reception of said ridges and annular projecting bands arranged at the opposite ends ¹⁰ of said V-shaped furrows for entering said channels of the first mentioned roller.

I hereby sign my name to this specification.

HUGH WALLACE AITKEN.
